UNITED STATES PATENT OFFICE

VASILIOS S. MACKRES, OF BROCKTON, MASSACHUSETTS

APPARATUS FOR CLEANING GLASSWARE

Application filed September 30, 1927. Serial No. 223,213.

The present invention relates to an apparatus for cleaning glassware used in dispensing foods and beverages.

The installation of the apparatus disclosed by me in my application Serial No. 220,652, filed September 20, 1927, necessitates the forming of a hole in the bottom of the water tank with which soda fountains are usually provided. It has been found that this creates sales resistance, as there is no way for the salesman to demonstrate the practicability of said apparatus without first cutting a hole in the bottom of the water tank, which is something the prospective customer is reluctant to have the salesman do.

The object of the present invention is to produce an apparatus for cleaning glassware, of the rotatable and longitudinally reciprocatable brush-supporting spindle type which may be installed in the water tank without structural change therein.

To the accomplishment of this object and such others as may hereinafter appear, the various features of the present invention relate to certain devices, combinations and arrangements of parts fully set forth hereinafter and then described broadly and in detail in the appending claims.

The various features of the present invention will be best understood from an inspection of the accompanying drawings illustrating the best form of the invention at present known to the inventor in which:

Figure 1 is an elevation of the apparatus secured in position to the bottom of a water tank which is sectionally detailed.

Fig. 2 is a sectional elevation of the apparatus, the brushes being removed, and

Fig. 3 is a detail in elevation of the frusto-conical spring.

Fig. 4 is a plan view on a reduced scale of a portion of the apparatus, illustrating the brush construction.

Referring to the drawings, the piece of glassware (not shown) is cleaned by a brush 13 which engages the interior bottom and sides of the glass and by two brushes 14 which engage the exterior of the glass adjacent the mouth thereof. These brushes

and the resilient supporting arms therefor are described in detail in my application hereinbefore referred to. The brushes 13 and 14 are supported from a spindle 15 having a spiral surface 16 which engages a spiral surface 17 formed centrally in a nut 18 carried by the smaller base of a frusto-conical cage 19. The interior of the larger base of the cage 19 is provided with threads which engage similar threads on the exterior of an open column 20 projecting vertically from a square piece of material such as the plinth 21 which engages the bottom of the tank 22.

In order to maintain the spindle 15 normally elevated, a frusto-conical spring coil 23 is interposed between the plinth and a collar 24 which is held on the lower end of the spindle 15 by means of suitable adjusting and locking nuts 25. The larger base 26 of the frusto-conical spring coil 22 engages the angle between the bottom of the plinth 21 and the interior of the column 20 and the smaller base of the frusto-conical spring coil engages the collar 24.

In operation the tank 22 is filled with clean water to which is added soap or a cleaning compound. The glass to be cleaned is then positioned on the rubber brushes which are normally submerged in the cleaning fluid. The mouth of the glass, as it is positioned between the brushes 13 and 14, contacts only with rubber so that chipping or breaking of the mouth of the glass is avoided. When the glass is positioned between the brushes 13 and 14, the pin 26 of bakelite or hard rubber engages the bottom of the glass. Downward pressure on the glass causes the spindle to reciprocate longitudinally through the unit 18 which, through engagement with the spiral 16, rotates the spindle 15 thus causing the brushes to rotate relatively to the glass. The brushes 13 and 14 are rendered slippery enough by the cleaning fluid to rotate readily on the glass without, however, nullifying completely their frictional engagement with the glass sufficient to rub it clean. It must be understood that the positioning of the glass between the brushes 13 and 14 and

the reciprocating of the spindle 15 occurs in one continuous downward movement of the glass held in the hands of the operative. At the bottom of its stroke the pressure on the spindle 15 is released. The compressed spring 23 then reverses the direction of movement of the spindle to return it to its original normal position. During the return of the spindle to normal position the brushes 13 and 14 rotate on the glass to complete the cleaning thereof. As shown in Fig. 2, the frusto-conical spring 23 does not flatten into a single plane, but retains its frusto-conical formation at the limit of downward movement of the spindle 15. With this construction the spring 23 acts as a thrust bearing for the spindle 15 to insure the rotation and reciprocation of the spindle 15 in the nut 18 without binding.

It will be clear to those skilled in the art, and with the general objects of the present invention in view, that changes may be made in the details of construction, the described and illustrated embodiment thereof being intended as an exploitation of its underlying essentials, the features whereof are definitely stated in their true scope in the claims hereto appended.

What is claimed as new is:

- 30 1. In an apparatus for cleaning glassware used in dispensing food and beverages, a support, a cylindrical wall projecting vertically from the support, a casing secured to the exterior of the wall, a stationary nut secured to the casing, a brush supporting spindle mounted for rotation and longitudinal reciprocation in the nut, a collar secured to the spindle, and a frusto-conical spring having its larger base engaged with the support within the cylindrical wall and its smaller base engaged with the collar.
- 35 2. In an apparatus for cleaning glassware used in dispensing food and beverages, a plinth adapted to engage with the bottom 40 of a tank, an open column integrally connected to the plinth and provided with external threads, a frusto-conical casing provided with internal threads on its larger base engaged with the threads on the column, a stationary nut secured to the casing, 45 a brush supporting spindle mounted for rotation and longitudinal reciprocation in the nut, a collar secured to the spindle, and a frusto-conical spring having its larger 50 base engaged with the plinth within the column and its smaller base engaged with the collar.

In testimony whereof I have signed my name to this specification.
